Hugh Brooks
Inventor:

UNITED STATES PATENT OFFICE.

HUGH BROOKS, OF GLASGOW, MONTANA.

SHOE-HORN.

1,224,846.

Specification of Letters Patent.

Patented May 1, 1917.

Application filed June 1, 1915. Serial No. 31,582.

To all whom it may concern:

Be it known that I, HUGH BROOKS, a citizen of the United States, residing at Glasgow, in the county of Valley and State of Montana, have invented certain Improvements in Shoe-Horns; and I do hereby declare the following to be a full, clear, and exact description of the invention, such as will enable others skilled in the art to 10 which it appertains to make and use the same.

The general object of this invention is to admit of the application of shoes or slippers to the feet and also the application of over- 15 shoes to the ordinary shoes, to be more easily conveniently and expeditiously carried out; and to this end the invention consists of a tubular body having a shoe-horn located at one end thereof, adapted to be positioned 20 within the shoe, slipper or rubber, and a longitudinally slideable jaw located within the body and normally held in spaced engagement with the shoe horn, and a lever carried by the body and having engagement 25 with the sliding jaw and adapted to force the latter in the direction of the shoe horn, whereby to admit of the clamping of the heel counter between the jaw and the shoe horn.

With the above and other objects in view as will more fully appear from the embodiment of my invention, of which the following is a specification reference being had to the accompanying drawings forming a part 35 thereof, in which:

Figure 1 is a side view of the device applied to the heel of a slipper.

Fig. 2 is a longitudinal sectional view thereof.

Fig. 3 is a transverse section taken on the line A—A of Fig. 1.

Fig. 4 is a detail sectional view of the clamping jaw 10.

Referring to the drawings more in detail the numeral 1 designates a tubular body member, provided with an enlarged head 2, upon which is mounted a shoe horn 3, the said shoe horn being secured to the head by means of a suitable fastening 45 element 4, the opposite end of the body 1 being provided with a handle 5. The head 2 is provided, at a point below the point of connection with the shoe horn 3, with a recess 6 which opens into 55 the opposite sides and the bottom of the head 2, and is spaced from the interior

of the tubular body 1 by means of vertical wall 7, the said wall 7 having an opening 8 therein communicating with the recess 6 and interior of the 60 body 1.

Slidably mounted within the body is a rod 9 being extended through the opening in the wall 7 and provided with substantially semi-circular clamping jaw 10. The rod 9 has mounted thereon an expansion helical spring 11, one end of the spring bearing against the adjacent face of the wall 7 and the opposite end bearing against a pin 12 which extends 70 transversely through the rod 9, at a point adjacent the rear end of the rod, and normally holds the jaw 10 in spaced relation to the shoe horn 3, the said pin 12 having one end projecting below the rod 9 and adapted to engage against a pin 13 which passes transversely through the body, so as to limit the movement of the rod.

The body 1 has formed thereon, at a 80 point substantially below the point of junction with the handle 5, a pair of depending ears 14. A lever 15 is disposed below the handle 5 and has one end provided with an enlarged head 16, 85 the said head being positioned between the ears 14 and pivoted therebetween by means of a pivot pin 17, which has its opposite ends located within the ears 14. The free end of the head 16 is provided 90 with a cut-away portion so as to provide a vertical shoulder 18, designed to bear against the adjacent or rear end of the rod 9, and a horizontally extending shoulder 19 which is positioned below the 95 tubular body and underlies a pair of depending flanges 20 and 21 formed on the inner surface of the body. The lever 15, when in normal inoperative position extends downwardly at an angle to the handle 5, by virtue of the pressure exerted thereon by the rod 9, and when in this position, the shoulder 19 is adapted to engage the under surface of the flanges 20 and 21 and limit the downward 100 movement of the lever.

This engagement between the shoulder 19 and the flanges 20 and 21, also prevent strain being exerted on the pins 12 and 13, should the lever 15 descend with considerable force.

In operation the lower end of the shoe

horn —3— is positioned within the heel counter of the shoe or rubber as shown in Fig. 1, and the lever —15— is drawn upwardly, resulting in the forward movement 5 of the rod —9— and positioning of the jaw —10— in engagement with the outer surface of the heel counter, so that the said heel counter may be clamped between the jaw and the horn. When the device is so positioned, upward pull is exerted thereon, which results in easy and expeditious application of the shoe or rubber, as the case may be, to the foot or ordinary shoe.

The horn —3— is provided with a pair 15 of curved extensions —22— and —23—, which are adapted, when the horn is positioned within the heel counter of the shoe, to engage along the inner surface of the sides of the counter, and the opposite ends 20 of the jaw —10— are of such length that when the jaw is in engagement with the outer surface of the counter the said ends will extend along the side of the counter for the entire length of the extensions —22— 25 and —23—. This construction permits of a large area of the heel counter being clamped between the jaw and the horn —3—, and overcomes any danger of injury being done to the counter. When it is desired to remove the device from the shoe, the 30

pressure is released on the lever —15—, whereby permitting the spring —4— to expand and to withdraw the jaw —10— from engagement with the heel counter.

What is claimed is:

1. A device of the class described comprising a tubular body, a shoe horn carried by the body and provided with a pair of curved extensions, said extensions being adapted when the shoe horn is positioned within the shoe to engage along the inner surface of the sides of the heel counter of the shoe, a semi-circular jaw slidably mounted upon the body and adapted when in one position to engage the outer surface of the sides of the heel counter, at points opposite the shoe horn and the curved extensions, and means for operating the said movable jaw. 40

2. A device of the class described comprising a tubular body, a shoe horn carried by the body, a jaw in said body adapted to straddle said horn, and means for longitudinally sliding said jaw in said body. 50

In testimony whereof, I affix my signature in presence of two witnesses.

HUGH BROOKS.

Witnesses:

C. F. KENNEY,
C. D. ARNOT.
